(57) **CLAIM**

The ornamental design for a control switch, as shown and described.

DESCRIPTION

FIG. 1 is a top plan view of a control switch showing our new design;

FIG. 2 is a bottom plan view thereof;

FIG. 3 is a left side view thereof;

FIG. 4 is a right side view thereof;

FIG. 5 is a front view thereof;

FIG. 6 is a rear view thereof; and,

FIG. 7 is a front perspective view thereof.
